UNITED STATES PATENT OFFICE

HARPER A. REYNOLDS, OF EAST CLEVELAND, OHIO, ASSIGNOR TO THE H. N. WHITE COMPANY, OF CLEVELAND, OHIO, A CORPORATION OF OHIO

BALANCER

Application filed May 10, 1929. Serial No. 361,989.

My invention relates to balancers, and more particularly to a type of balancer readily adaptable for use on instruments such as trombones and the like, and the principal object of my invention is to provide a new and improved device of this type. In the drawings accompanying this specification and forming a part of this application I have shown, for purposes of illustration, one form which my invention may assume, and in these drawings:

Figure 1 is a side elevation of this illustrative embodiment of my invention,

Figure 2 is a section taken on the line 2—2 of Figure 1, while

Figure 3 is a section taken on the line 3—3 of Figure 2.

The use of a balancer on musical instruments such as trombones is quite common for properly balancing the instrument to make possible a rapid execution of the instrument. There are several types of balancers now in common use on trombones, but such balancers are either of the built-in type or are of a type not easily removable. I have discovered that a balancer, readily adaptable for use on such instruments as trombones and the like, may be easily and cheaply constructed in a manner to provide an easily and quickly attachable and detachable balancer so that the balancer best adapted for the use of each individual player may be readily attached to the instrument.

The embodiment of my invention herein shown comprises a trombone 11 having an upper tube 12 terminating at one end in a bell section 14, a lower tube 13 joined to the upper tube 12 by a curved member 15, and a slide 16 having an upper tube 17 and a lower tube 18. The tubes 17 and 18 of the slide 16 are adapted to slide respectively in a short tube 19 and in the lower tube 13, while a mouth piece 20 is secured to the end of the short tube 19 opposite from the slide 16. A brace 21 joins the upper tube 17 and the lower tube 18 of the slide 16 and another brace 34 joins the upper tube 12 and the lower tube 13 while a similar brace 22 joins the short tube 19 and the lower tube 13 and two other braces 23 and 33 join the upper tube 12 and the lower tube

13, and it is to this brace 33 that I prefer to apply my balancer.

I provide a flat balancer 24 having a flat circular base 25 provided centrally with a circular outwardly extending portion 26 provided exteriorly along its top portion with threads 27 and with a radially extending groove 28. A first ring 29 is adapted to fit around the outwardly extending portion 26 of the base 25 and is provided centrally with a corresponding groove 30, while a flat cover 31, cored out centrally and there provided with threads 32, is adapted to cooperate with the threads 27 on the outwardly extending portion 26 of the base 25.

The balancer 24 is assembled on the brace 33 of the trombone 11 by first placing the base 25 of the balancer 24 against the brace 33 in such a manner that the groove 28 of the base 25 fits around the brace 33, then while the base 25 is held in this position the ring 29 is fitted around the outwardly extending portion 26 of the base 25 with the groove 30 of the ring 29 fitting securely over the brace 33, then the cover 31 is placed over the ring 29 and the threads 32 on the cover 31 are caused to engage the threads 27 on the outwardly extending portion 26, and then the cover 31 is turned until the threads 32 and 27 have drawn the base 25 to the cover 31 to hold the ring 29 firmly there-between and therefore hold the balancer 24 firmly on the brace 33.

From the foregoing it will be obvious to those skilled in the art that I have provided a balancer which may be quickly and easily attached and detached from the trombone in order that a balancer particularly adapted for the use of the individual player may be readily mounted on the trombone to properly poise the instrument in the player's left hand without exertion, the balancers being made in different weights.

It further will be obvious to those skilled in the art that the embodiment of my invention herein disclosed accomplishes the principal object of my invention.

At the same time it also will be obvious to those skilled in the art that the particular embodiment of my invention herein shown

and described may be variously changed, modified, and used, all without departing from the spirit of my invention or sacrificing the advantages thereof, and it therefore will be understood that the disclosure herein is illustrative only, and that my invention is not limited thereto.

I claim:

1. A balancer, as for use on trombones, and to be applied as to a brace connecting two tubes of said trombone, comprising: a base recessed to receive said brace; cover means adapted to cooperate with said base to clamp said brace therebetween; and cooperating screwthreads on said base and said cover means for releasably securing said cover means to said base in adjustable relation.

2. A balancer, as for use on trombones, and to be applied as to a brace connecting two tubes of said trombone, comprising: a base recessed to receive said brace; a ring recessed to receive said brace and adapted to fit around a part of said base; cover means adapted to fit over said ring to clamp said brace between said ring and said base; and means for securing said cover means to said base in clamping relation.

3. A balancer, as for use on trombones, and to be applied as to a brace connecting two tubes of said trombone, comprising: a base recessed to receive said brace; a ring recessed to receive said brace and adapted to fit around a part of said base; cover means adapted to fit over said ring to clamp said brace between said ring and said base; and coacting means formed on said base and said cover means for securing said cover means to said base in clamping relation.

4. A balancer, as for use on trombones, and to be applied as to a brace connecting two tubes of said trombone, comprising: a base recessed to receive said brace; a ring recessed to receive said brace and adapted to fit around a part of said base; cover means adapted to fit over said ring to clamp said brace between said ring and said base; and cooperating screwthreads on said base and said cover means for releasably securing said cover means to said base in adjustable relation.

5. A balancer, as for use on trombones, and to be applied as to a brace connecting two tubes of said trombone, comprising: a base recessed to receive said brace and provided with an upstanding section; cover means adapted to cooperate with said base to clamp said brace therebetween; and co-acting means formed on said upstanding section of said base and said cover means for securing said cover means to said upstanding section of said base in clamping relation.

6. A balancer, as for use on trombones, and to be applied as to a brace connecting two tubes of said trombone, comprising: a base recessed to receive said brace and provided with an upstanding section; cover means

adapted to cooperate with said base to clamp said brace therebetween; and cooperating screwthreads on said upstanding section of said base and said cover means for releasably securing said cover means to said upstanding section of said base in adjustable relation. 70

7. A balancer, as for use on trombones, and to be applied as to a brace connecting two tubes of said trombone, comprising: a base recessed to receive said brace and provided with an upstanding section; a ring recessed to receive said brace and adapted to fit around said upstanding section of said base; cover means adapted to fit over said ring to clamp said brace between said ring and said base; and coacting means formed on said upstanding section of said base and said cover means for securing said cover means to said base in clamping relation. 75

8. A balancer, as for use on a wind musical instrument, and to be applied to a portion of said instrument, comprising: a base recessed to receive said portion; cover means adapted to cooperate with said base to clamp said portion therebetween; and cooperating screwthreads on said base and said cover means for releasably securing said cover means to said base in adjustable relation. 80

9. A balancer, as for use on a wind musical instrument, and to be applied to a portion of said instrument, comprising: a base recessed to receive said portion; a ring recessed to receive said portion and adapted to fit around a part of said base; cover means adapted to fit over said ring to clamp said portion between said ring and said base; and means for securing said cover means to said base in clamping relation. 85

10. A balancer, as for use on a wind musical instrument, and to be applied to a portion of said instrument, comprising: a base recessed to receive said portion; a ring recessed to receive said portion and adapted to fit around a part of said base; cover means adapted to fit over said ring to clamp said portion between said ring and said base; and co-acting means formed on said base and said cover means for securing said cover means to said base in clamping relation. 90

In testimony whereof I hereunto affix my signature.

HARPER A. REYNOLDS.
